UNITED STATES PATENT OFFICE.

GEORGE A. LAWRENCE, OF NEW YORK, N. Y., AND EDWARD J. FROST, OF PHILADELPHIA, PENNSYLVANIA.

ORE-REDUCING FURNACE.

SPECIFICATION forming part of Letters Patent No. 287,945, dated November 6, 1883.

Application filed December 27, 1881. (No model.)

To all whom it may concern:

Be it known that we, GEORGE A. LAWRENCE, a citizen of the United States, residing at New York, in the county and State of New York, and EDWARD J. FROST, a citizen of the United States, residing at Philadelphia, in the county of Philadelphia and State of Pennsylvania, have invented certain new and useful Improvements in Ore-Reducing Furnaces; and we do hereby declare that the following is a full, clear, and exact description of the same, which will enable others skilled in the art to which the invention appertains to make and use the same, reference being had to the accompanying drawings, forming part of this specification.

Our invention relates to a furnace for the reduction of pulverized ores, its objects being to produce an intense heat in a combustion and reducing chamber by means of a blast of pulverized fuel, and to cause the heat so produced to not only act upon pulverized ore introduced in a cloud into the chamber, but also to heat a decomposer arranged inside of said chamber, for the production of gas from suitable materials introduced therein, which gas is discharged within the chamber, and adds by its combustion to the intensity of the heat for the reduction of the ore.

The invention consists in a novel combination of devices for accomplishing the objects referred to, as will be hereinafter fully described, and pointed out in the appended claims.

In the accompanying drawings, Figure 1 is a view, partially in vertical section, illustrating our improved furnace and its attachments. Fig. 2 is a horizontal section on line $x-x$ of Fig. 1. Fig. 3 is a detail view, mainly in section, of the coil and injector. Fig. 4 is a sectional view of a portion of the blast-pipe, showing the check-valve therein. Fig. 5 is a section of the blast-pipe in the plane indicated by line $y-y$ of Fig. 4.

Referring to Fig. 1, the letter D designates a combustion and reducing chamber inclosed by walls of any suitable refractory material, and d is a flue leading from the upper portion of this chamber and under a boiler, H, which

is supported adjacent to the combustion and reducing chamber by masonry or other suitable means.

The letter B indicates a blast-pipe leading from a blower, A, and having two branches, b b, which enter the lower portion of the chamber D at opposite sides, and terminate in upturned portions E, somewhat inclined toward each other near the center of said cupola.

A hopper, C, is connected with the blast-pipe B by means of a short pipe, c, and suitably mounted at the center of the hopper and of pipe c is a vertical shaft, C', the lower portion of which carries a feed-screw, c', and the upper portion of which is provided with radial arms c''. The hopper is for supplying the blast-pipe with pulverized coal, which is properly agitated by the arms c'', to prevent packing, and is fed forward by the screw c'. The shaft C' receives rotary motion from a suitably-gearred shaft, and its speed may be regulated in the ordinary manner by an arrangement of cone-pulleys, R R, and a belt connecting the same.

Between the hopper and the branch pipes b b the blast-pipe is provided with a pivoted check-valve, Q, which normally rests upon an inclined seat, q, and has one of its pivots projecting outside the pipe, and provided with an inclined arm, upon which is arranged an adjustable weight, Q'.

In the lower portion of the chamber D is arranged a vertical pipe-coil, F, the upper turns of which are perforated, as shown at f, said coil serving as a decomposer for the conversion of steam into gas. The lower terminal of the coil is connected to a pipe, f', which extends through the wall of the cupola and connects with the eduction-spout of an injector, I, from the induction-nozzle of which a pipe, G', leads to a superheating return-pipe, G, arranged in the flue under the boiler and connected with the steam-space of said boiler. The injector is provided with an air-inlet pipe, J, and may be also connected by a dip-pipe, as shown at K, with a tank, L, to hold oil.

Through the roof of the chamber D is arranged a vertical hollow shaft, M, suitably

- supported in a journal-box carried by a bracket, *m*. At its lower end, within the chamber, the shaft *M* carries a hollow perforated disk, *O*, with the interior of which the bore of the shaft *M* is in free communication. Upon the upper end of the shaft is mounted a hopper, *P*, and below the hopper the shaft is provided with a belt-pulley, *N*, which may receive motion from a belt, *N'*.
- 10 The operation of the apparatus as now explained is as follows: The boiler being first properly supplied with water, the hopper *C* is filled with properly-pulverized coal, and the blower and shaft *C* put in motion, the valve of the blower being opened. The check-valve *Q* is opened by the blast, and two jets of the pulverized coal mixed with air are forced into the chamber *D* inside of the coal. These jets are then ignited through a door, (not shown 15 in the drawings,) and a flame fills or partially fills the cupola, according to the quantity of fuel supplied, the feed being regulated by the adjustment of one of the cone-pulleys *R*. The heat passing from the cupola through flue *d* raises steam in the boiler and superheats said steam as it passes through the return-pipe *G* to pipe *G'* and the injector. If only superheated steam and air are to be used, the valve in pipe *K* is closed and that in pipe *J* opened, 20 and then a mixture of superheated steam and air will be forced through the injector, and the steam will be converted into hydrogen and oxygen gases as it traverses the coil *F*. The hydrogen gas, escaping through the perforations *f*, becomes ignited, and adds greatly to the intensity of the heat produced by the combustion of the coal-dust. When a proper degree of heat is reached within the chamber *D*, the shaft *M* is started into rapid rotation, and 25 into the hopper *P* is fed the pulverized ore, which passes through the hollow shaft *M*, and is discharged in a cloud by the rapidly-rotating hollow perforated disk *O*. To facilitate the production of gas, especially in the early 30 stage of the operation, the cock in the pipe *K* may be opened, when the blast of superheated steam will draw up oil through the pipe *K* and force it through the injector in the form of vapor. The metallic portion of the ore is 35 melted out and falls upon the hearth of the chamber, from which it may be collected in any suitable manner, while the most of the silicious and earthy portions of the ore are carried off by the blast through the flue *d*. 40 The check-valve *Q*, being properly balanced, will close, should the back-pressure of the blast-pipe be sufficient to counteract the blast, so that the coal-dust in the hopper *C* will not be ignited.
- 45 We have not shown any mechanical connection between the shaft *M*, cone-pulleys, and blower, as it will be readily understood that they may have motion communicated to them by any of the ordinary suitable means.
- 50 We are aware that a furnace has been provided heretofore with means of introducing a blast of pulverized fuel thereto, and also that pulverized ore has been introduced in a cloud into a combustion and reducing chamber. We are also aware that a coil for converting suitable materials into gas has been located in a furnace, and that a coil has been arranged around the outside of a furnace-chamber, and provided with openings to the interior of the chamber, for the purpose of discharging there- 55 in a gas produced by a generator independent of the furnace. We are further aware that superheated steam and a hydrocarbon gas have been introduced together into an ore-reducing furnace, and that such furnace has been provided with an outside superheater, from which superheated steam may be discharged among crushed ore passing through a passage to the furnace. We do not claim any of these inventions. 60
- Having now described our invention and explained the operation thereof, we claim—
1. In an apparatus for reducing ores, the combination, with a combustion and reducing chamber, means for introducing a blast of pulverized fuel thereto, and separate means for introducing pulverized ore thereto, of a decomposer arranged within said chamber and having openings to the interior thereof, and means for supplying to said decomposer materials which will be converted into combustible gas by the action of heat thereon, the whole arranged and adapted to operate substantially as described. 65
2. In an apparatus for reducing ores, the combination, with the combustion and reducing chamber, of the blast-pipe and connected blower and feed-hopper for supplying pulverized fuel to the blast-pipe, the perforated coil *F*, arranged within the chamber, means for forcing into said coil a supply of material to be converted into gas therein, and means for discharging a cloud of pulverized ore into said chamber, substantially as described. 70
3. In an apparatus for reducing ores, the combination, with the combustion and reducing chamber, fuel-blast devices, and the decomposer arranged within said chamber and provided with openings to the interior thereof, of the boiler arranged to receive heat from said chamber, and connected with said decomposer by a suitable steam-pipe, and means for introducing ore into said chamber, substantially as described. 75
4. In an apparatus for reducing ores, the combination, with the combustion-chamber provided with means for introducing ore and producing heat therein, the perforated pipe-coil arranged in said chamber, and the boiler connected with said pipe-coil by a steam-pipe, of an injector arranged in said steam-pipe to discharge into said coil, and one or more additional pipes connected with said injector for supplying a fluid or fluids to accompany the steam, substantially as described. 80
5. In an apparatus for reducing ores, the combination, with the combustion-chamber,

means for introducing ore and pulverized fuel
therein, the perforated pipe-coil within said
chamber, and the boiler connected with said
pipe-coil by a steam-pipe, of an injector ar-
5 ranged in said steam-pipe, and an oil-tank
connected with said injector by a suitable pipe,
substantially as and for the purpose set forth.

In testimony whereof we affix our signatures
in the presence of two witnesses.

GEORGE A. LAWRENCE.
EDWARD J. FROST.
